UNITED STATES PATENT OFFICE

2,128,674

FAUCET SEALING DEVICE

Henry Hughes, Toronto, Ontario, Canada, assignor to James Morrison Brass Manufacturing Company Limited, Toronto, Ontario, Canada, an incorporated company

Application October 5, 1936, Serial No. 104,059

1 Claim. (Cl. 225—5)

This invention relates to new and useful improvements in faucets particularly adapted for application to beer kegs. It has become the practice, in the shipping and sale of beer by the 5 keg to provide the keg with a tapping device such as described and illustrated in United States Letters Patent No. 2,008,642 granted July 16th, 1935, to the James Morrison Brass Manufacturing Company, Limited, the assignee of my entire 10 interest in the invention described in the said Letters Patent. The general object of the invention therein described is to provide a faucet for beer kegs which may be shipped with its container and to this end it may be built in the 15 keg or applied to it at the time the container is filled with the contents to be shipped therein and dispensed therefrom and thus supply the consignee with a pouring or dispensing device that is immediately available for use.

20 However, since beer and certain other liquids are subject to a special tax which is paid in the form of stamps attached to the container in which the same are shipped and sold, it being compulsory to so attach the said stamp to the 25 container that the stamp will be mutilated and destroyed when the container is opened.

The object of my present invention is to provide faucets used in the dispensing of beer and other liquids which are subject to such tax with 30 a device for mutilating and destroying said special stamps so that they cannot be used again when the faucet has once been opened.

The manner in which I accomplish this object is set forth in the following description and illustrated in the accompanying drawing in which:

35 Fig. 1 is a fragmentary vertical section of a keg showing a faucet applied thereto which embodies the subject matter of this invention.

Fig. 2 is a plan view of Fig. 1 and

40 Fig. 3 is a perspective view of Fig. 1, showing a seal being broken by my device.

Like characters of reference refer to like parts throughout the specification and drawing.

45 For the purpose of fully illustrating my invention and the manner in which it is constructed and employed, I propose to describe it as used in connection with a faucet constructed in accordance with the said Letters Patent No. 2,008,642 but it is to be understood that I do not limit 50 my invention to such construction as it will be apparent that the same can be employed with other types of faucets. Since the construction of that invention is well known, I will only describe such parts of the faucets as is necessary to 55 clearly illustrate the construction and use of my present invention.

In the drawing 10 indicates the side of a keg which is constructed in the usual manner of

staves, 11 indicates the chime and 12 indicates the end closure wall which is located inwardly from the chime and has mounted thereon a faucet which comprises a hollow housing 13 provided with a swivel spigot 14 and a valve operating handle 15. Attached to the underside of the valve handle 15 is the sealing and seal breaking device which is the subject matter of the present invention which comprises a plate 16 engageable with the outer surface of the end closure wall 12, and arm 17 one end of which is attached to the said plate and the other end securely attached to the valve handle 15, the portion of the arm between the operating handle and the plate being curved or bent so that when the valve operating handle 15 is in closed position, the plate 16 will lie flat against the outer surface of the end closure wall 12. It will be understood, of course, that the said arm and plate, if desired, may be made an integral part of the valve operating handle. 20 Since some types of faucet, employed for dispensing liquid do not control the discharge of liquid by a separate valve as illustrated in the said patent but control it by the swivel spigot, it will be necessary in such cases to attach the arm 17 to the swivel spigot, and in which case the spout of the spigot serves as the valve operating handle.

The valve operating handle is sealed in its closed position, as illustrated in Fig. 2 by pasting the stamp which is indicated at 18 over the plate 30 and to the end closure wall. When the valve operating handle is moved towards its open position, as illustrated in Fig. 3, a portion of the stamp comes away with the plate thus mutilating the tax stamp so that it cannot be used again 35 for the same or any other purpose.

In the foregoing description I have set forth the preferred embodiment of my invention but I do not limit my invention to the particular construction shown and described, as it will be apparent that the same is subject to alterations and modifications without departing from the scope of the appended claim.

Having thus fully described my invention what I claim is new and desire to secure by Letters 45 Patent is:

A faucet for liquid containers comprising a housing mountable on the wall of a keg, a swivel spigot secured in said housing, a valve operating handle attached to said housing, and means permanently attached to said handle for sealing the handle to a wall of said keg, said means comprising a plate engageable with the wall when said handle is in closed position and an arm uniting said plate to said handle and moveable therewith, 50 said plate being adapted to break and mutilate a seal when said handle is moved in any direction.

HENRY HUGHES.
